UNITED STATES PATENT OFFICE.

FRANK S. PARKER, OF MERIDEN, CONNECTICUT, ASSIGNOR TO EDWARD MILLER & COMPANY, OF MERIDEN, CONNECTICUT, A CORPORATION OF CONNECTICUT.

GAS-REGULATOR FOR BUNSEN BURNERS.

964,804.

Specification of Letters Patent. Patented July 19, 1910.

Application filed March 31, 1910. Serial No. 552,495.

To all whom it may concern:

Be it known that I, FRANK S. PARKER, a citizen of the United States, residing at Meriden, county of New Haven, State of Connecticut, have invented certain new and useful Improvements in Gas-Regulators for Bunsen Burners, of which the following is a full, clear, and exact description.

My invention relates to a gas regulating device for Bunsen burners, the object of the invention being to provide a simple and effective regulator mechanism whereby very fine adjustment can be effected.

In the accompanying drawings Figure 1 is a side elevation, relatively enlarged. Fig. 2 is a vertical section showing the parts in one position. Fig. 3 is a similar view showing the parts in another position. Fig. 4 is a view of the inner end of the manually-operable element detached from the body of the gas tip. Fig. 5 is a side elevation of the valve detached.

1 is the main body of the gas tip, which is usually provided with the screw-threaded portion 2, onto which the Bunsen tube (not shown) may be screwed.

3 is the usual internal screw-thread, by which the tip is secured to the gas fixture.

4 is a small central outlet for the gas in the top of the tip 1.

Extending longitudinally in the body of the tip 1 is an enlarged valve receiving cavity, and arranged therein is a conical valve 5 having a relatively enlarged guide body 6, which may have any desired number of longitudinal clearance passages in its outer side to permit gas to flow past said body toward the outlet 4. The guide body 6 so fits the bore of the tip body 1 as to properly center the point of the conical valve 5 with respect to the gas outlet 4. The lower end of the guide body 6 is slotted longitudinally, the bottom of the slot being formed on an incline, as shown at 7.

8 is a nut preferably having a beveled incline to correspond with the bevel 7. This nut is cut away on opposite sides, as best seen in Fig. 4, so that it will stand in the slotted lower end of the guide body 6, and not turn therein.

9 is the stem of a controlling device, preferably fitted with a knurled finger-piece 10 and having a threaded forward end 11, upon which the nut 8 is mounted.

12 is a stuffing box.

14 is a flange between the stuffing box and the nut, serving to hold the stem 9 against longitudinal movement when the stuffing box is in place.

15 is a spring arranged between the upper end of the guide body 6 and the valve 5 and the overstanding domed wall of the tip body 1, said spring operating to push the valve 5 downwardly against the nut 8.

The adjustment of the valve is effected as follows: Rotation of the finger-piece 10 in the proper direction will cause the nut 8 to advance on the thread 11. The nut 8 moving against the incline 7 pushes the valve upwardly from the position shown in Fig. 2 toward the position shown in Fig. 3. This movement tends to reduce the size of the gas outlet 4. Reverse rotation of the finger-piece 10 moves the nut in an opposite direction on the thread 11, whereupon the spring 15 operates to move the valve 5 back to its original position, said movement opening the gas outlet 4. It will be observed that a substantial rotation of the finger-piece 10 imparts but relatively slight longitudinal movement of the nut 8 on the screw 11, and hence since the incline 7 is what may be termed an "easy incline", it follows that a substantial turn of the finger-piece 10 imparts but very slight movement to the valve 15. Accordingly it is possible to secure the most accurate adjustment by this very simple and relatively inexpensive means.

What I claim is:

1. In a gas regulator, a tip, a passage therethrough, a contracted gas outlet at one end thereof, a valve for said gas outlet longitudinally guided and movable in said passage, a spring operating to move the valve in one direction, an incline on the valve, and a manually operable nut movable transversely of the valve and bearing against said incline and arranged to move said valve in a direction opposite to the direction of movement effected by said spring.

2. In a gas regulating device, a tip having a passage therethrough and a contracted gas outlet at one end thereof communicating with said passage, a tapered valve for said gas outlet longitudinally guided and movable in said passage, a spring operating to move the valve in one direction, and a device movable transversely in said guide pas-

sage to move said valve in an opposite direction, said device being operatively connected with said valve, the line of connection being oblique or inclined relatively to the direction of movement of the movable device, said device being in the form of a non-rotatable nut with a rotatable screw-threaded support therefor, the latter being arranged for manual manipulation.

5 10 3. In a gas regulating device, a tip having a passage therethrough and having a contracted outlet at one end of said passage, a tapered valve mounted to slide in said passage, the body portion of said valve be-

ing guided by the walls thereof, said body 15 portion having a longitudinal slot, the end of said slot having an inclined wall, a nut standing in said slot and arranged to engage said incline, a screw-threaded rotatable mounting for said nut whereby the 20 latter may be moved toward and from said incline, and a spring acting on said valve to hold said incline against said nut.
